UNITED STATES PATENT OFFICE.

MARK P. LAYTON AND JAMES W. VAN DOREN, OF MINONK, ILLINOIS.

DERAILER.

SPECIFICATION forming part of Letters Patent No. 735,534, dated August 4, 1903.

Application filed September 16, 1902. Serial No. 123,565. (No model.)

To all whom it may concern:

Be it known that we, MARK P. LAYTON and JAMES W. VAN DOREN, citizens of the United States, and both residents of Minonk, in the county of Woodford and State of Illinois, have invented a new and Improved Derailer, of which the following is a full, clear, and exact description.

This invention relates to a device for running railway rolling-stock from the rails. It is applicable in various connections, particularly on sidings or switches, so as to prevent the cars on the switch from being run back accidentally onto the main track.

One of the prime features of our invention lies in the entire automatic action of the derailer. Assuming that it be placed on a siding or switch, as cars are entered into the siding the derailer will not interfere therewith, but will automatically give way. Should, however, the cars be started in the opposite direction—that is to say, toward the main track—the derailer will throw the cars from the siding and prevent them from reaching the main rails.

The construction of the derailer is such that it may be moved from active into inactive position by the railway men whenever desired, and when so moved it will have no action upon the cars, no matter whether they be running into or out of the siding.

This specification is an exact description of one example of our invention, while the claims define the actual scope thereof.

Reference is to be had to the accompanying drawings, forming a part of this specification, in which similar characters of reference indicate corresponding parts in all the views.

Figure 1 is a perspective view of the invention. Fig. 2 is a plan view thereof. Fig. 3 is a section on the line 3 3 of Fig. 2, and Fig. 4 is a side view showing the derailer in inoperative position.

The device comprises a base-plate *a*, which is arranged to be fastened to the ties in the manner shown in Figs. 1 and 2 or in any other suitable manner. On this base-plate is formed a slideway *a'*, which is disposed slightly diagonally with respect to the rail. In this slideway is arranged a slide *b*, which has a stem *b'* fitted in the slideway and a spring *c* pressing the stem, so as to hold the slide

yieldingly in the active position shown in the drawings. The slideway *a'* has a raised or beaded portion *a²* at the top thereof, as best shown in Figs. 3 and 4, the stem *b* and spring *c* being received in a cavity formed in the slideway.

d indicates the derailing-plate, which is connected by a hinge *d'* with the slide *b* and which is normally adapted to lie over the bead *a²* and to extend inward over the ball of the rail. The said plate *d* has downwardly-projecting side flanges *d²*, which inclose the bead *a²*, and by this engagement of the parts *d²* and *a²* lateral movement of the plate *d* is prevented and undue strain on the hinge *d'* is avoided. At its free end the derailing-plate *d* is formed with an upwardly and outwardly inclined surface *d³*, adapted to bear the tread of the wheel, and a correspondingly-disposed surface *d⁴*, adapted to engage the flange of the wheel, so that should the car advance toward the derailer in the direction of the arrow *x* in Fig. 2 the wheel will ride up the surfaces *d³* and *d⁴* and be derailed. If, however, the car should approach the device in the direction of the arrow *y*, the outer side of the wheel will ride against the curved inner edge or face *d⁵* of the plate *d* and push said plate outward against the tension of the spring *c*, thus allowing the car to pass the derailer without disturbing the proper engagement of the wheels with the rail.

e indicates a pin which is passed through a boss *d⁶*, formed on one of the flanges *d²* of the plate *d* and surrounding an opening in said flange, so that said pin *e* may engage in a slot *a³*, formed in the bead *a²* and disposed longitudinally thereof. This slot limits the movement of the plate *d*, but allows it to assume the operative position (shown in Fig. 2) or the inoperative position, in which said plate is pushed sidewise to allow the wheel to pass. The tube or boss *d⁶* is formed with two opposite openings *d⁷*, one of which is shown in Fig. 4, and through these openings is adapted to be passed the hasp of a lock. (Indicated at *f* in Figs. 1 and 2.) This lock is also engaged with the pin *e*, and by these means the pin may be held in place and removed only by releasing the lock *f*. *g* indicates a chain or the like for fastening the pin *e* to one of the ties, so as to prevent the accidental loss

of the pin. When the pin *e* is withdrawn, the plate *d* may be thrown outward from the position shown in Fig. 2 to that shown in Fig. 4, in which position it will be wholly inactive.

5. In the use of the invention, assuming that it were applied to a siding in such a manner as to allow cars to be entered thereinto, but to prevent them from being accidentally moved off of the siding, the derailer should 10 be arranged so that the cars in entering into the siding will move in the direction of the arrow *y* in Fig. 2. Thus it will be seen that any number of cars may be pushed onto the siding without interference by the derailer. 15 Should, however, any of the cars be accidentally moved off of the siding in the direction of the arrow *x* in Fig. 2, if the cars are moving with sufficient velocity the wheels will ride up the surfaces *d*³ and *d*⁴ and be entirely 20 derailed. However, should the cars be moved at a low speed—for example, should a high wind cause the cars to move—as the wheels strike the inclined surfaces *d*³ and *d*⁴ the movement of the cars will be arrested, and 25 the derailer will then act as a bumper or stop. When the cars are to be intentionally removed from the siding, the railwayman in charge should release the lock *f* and remove the pin *e*. The derailing-plate *d* may then be thrown 30 out, as shown in Fig. 4, and the cars passed to and fro irrespective of the derailer.

Various changes in the form, proportions, and minor details of our invention may be resorted to at will without departing from 35 the spirit and scope thereof. Hence we consider ourselves entitled to all such variations as may lie within the intent of our claims.

Having thus described our invention, we claim as new and desire to secure by Letters 40 Patent—

1. The combination of a base, a slide thereon, a derailing member mounted to move with and on the slide, and means pressing the slide to hold the derailing member normally 45 in active position.
2. The combination of a base, a slide thereon, a derailing member mounted to move with and on the slide, and means pressing the slide to hold the derailing member normally in 50 active position, said derailing member having a face or edge disposed diagonally with respect to the longitudinal line of the rail.
3. The combination of a base having a slide-

way thereon and an upwardly-projected bead, a slide mounted in the slideway, a spring 55 pressing the slide, and a derailing-plate hingedly mounted on the slide and normally bearing on the bead.

4. The combination of a base having a slide-way thereon and an upwardly-projected bead, a slide mounted in the slideway, a spring 60 pressing the slide, a derailing-plate hingedly mounted on the slide and normally bearing on the bead, means for limiting the sliding movement of the derailing-plate, and a lock 65 for releasably holding said means in active position.

5. The combination of a base, a slide mounted thereon, means pressing the slide into active position, and a derailing member mounted 70 on the slide to move therewith and to move independently thereof.

6. In a derailer, the combination of a base, a derailing member, means for mounting the derailing member to slide on the base toward 75 and from the rail, and means yieldingly holding said derailing member normally into active position, the derailing member comprising a face normally extending diagonally across the ball of the rail, for the purpose 80 specified.

7. The combination of a base having a slot therein, a slide mounted on the base, a derailing member mounted to move with and 85 on the slide, and means carried on the derailing member and coacting with the walls of said slot for the purpose specified.

8. The combination of a base having a slot therein, a slide mounted on the base, a derailing member mounted to move with and 90 on the slide, and means carried on the derailing member and coacting with the walls of said slot for the purpose specified, said means comprising a boss on the derailing member, a pin fitted loosely in the boss and 95 running in the slot, and means for holding the pin removably in place.

In testimony whereof we have signed our names to this specification in the presence of two subscribing witnesses.
